Primary Examiner — Philip S Hyder*Assistant Examiner* — Cary M Robinson(74) Attorney, Agent, or Firm — Yee & Associates, P.C.(57) CLAIM

The ornamental design for a display screen with graphical user interface, as shown and described.

DESCRIPTION

FIG. 1 is a front view of a display screen with graphical user interface;

The dual set of outermost broken lines illustrate a display screen. The broken line showing of text, numbers, icons and boxes illustrate portions of the graphical user interface. None of the broken lines form part of the claimed design.
